UNITED STATES PATENT OFFICE.

CYRIL GEORGE MANCHA BENNETT, OF LONDON, AND SYDNEY HERBERT SMITH, OF WEST EALING, ENGLAND, ASSIGNORS TO THE BABCOCK & WILCOX COMPANY, OF BAYONNE, NEW JERSEY, A CORPORATION OF NEW JERSEY.

CHAIN GRATE.

1,206,197.

Specification of Letters Patent. Patented Nov. 28, 1916.

Application filed March 25, 1913. Serial No. 756,674.

To all whom it may concern:

Be it known that we, CYRIL GEORGE MANCHA BENNETT and SYDNEY HERBERT SMITH, subjects of the King of Great Britain, residing at 112 Holland road, London, W., England, and 24 Bradley Gardens, West Ealing, England, respectively, have invented certain new and useful Improvements in Chain Grates, of which the following is a specification.

Our invention relates to improvements in revolving chain grates very generally used in the furnaces of steam boilers, refuse destructors and for like purposes, and more particularly to that class of chain grate which is formed of a number of transverse series of links or firebars which are pivotally connected with their transverse supports at one end only and are so constructed that on the return journey toward the front of the furnace around the carriage on which they are mounted they turn like flap valves, thus dropping any collection of ashes or partially consumed fuel which may be dropped from the top portion of the chain on to the bottom portion. Owing to this action of the firebars which form the grate the stoker is self-cleaning while the firebars are kept cool and an easy path is provided for the entrance of the air to the top portion of the chain which is moving toward the back of the furnace.

From experience it is found that the life of the top part of a firebar, which carries the fuel to be burnt and therefore receives the greatest heat, is considerably less than the frame and hinge or hinges of said firebar.

The firebars of our invention are conveniently built up from a broad light framework which is pivotally mounted at one end on the transverse members or supports of the chain. This framework is provided with a separable top part which may be provided with air slots. This top part effectively protects the frame on which it is mounted while it can be changed or renewed by hand without disturbing either the frame or the transverse member of the chain on which said frame is pivoted. Owing to the breadth of the framework of the firebars as compared with the firebars

now usually employed in chain grates we reduce the number of joints in the chain and consequently we materially reduce the friction in working and at the same time bring about a large reduction of the riddling of small coal between said firebars.

Our invention is illustrated by way of example in the accompanying drawings in which—

Figure 1 is a plan view of a flap firebar; Fig. 2, a side view of Fig. 1; Fig. 3 a section on the line A—B of Fig. 1; Fig. 4 a detail plan view of the underside of a separable top; Fig. 5 a side view of Fig. 4; Fig. 6 a bottom plan view of the frame; and Fig. 7 is a side elevation, broken away and partly in section, of a complete chain grate illustrating a method of utilizing the invention.

The broad firebars of our invention are built up from a light framework 1 illustrated more particularly in Fig. 6 which is adapted to be pivotally mounted at one end on the transverse members or supports 2 of the chain. This framework 1 is provided with a separable top part 3 adapted to carry the fuel to be burnt. As shown the said top part 3 is preferably provided with air slots 4 which may vary in size and number, thus allowing of a chain grate which is fitted with such flap firebars being partially or wholly refitted with firebars having more or less air supply without disturbing the chain or the transverse members on which the firebars are mounted. The said top part 3 effectively protects the frame 1 on which it is mounted while it can be removed and renewed by hand without disturbing either the frame or the transverse member 2 of the chain on which said frame 1 is pivoted.

In order that said top part can be easily removed we may form at the inner or hinge end of the frame 1 an under-cut 5 as shown more particularly in Fig. 3 while the adjacent edge 6 of the removable top portion 3 is tapered outward so as to project into said under-cut edge when said top portion is in position in its frame as shown in Fig. 3. This under-cut edge 5 is adapted to retain said top portion in position when the firebars are passing into the position of use over the front end of the carriage on which the chain is mounted.

The said top portion 3 may be provided on its underside near the opposite end to its lip 6 with a lug 7 adapted to lie when in position against the cross bar 8 of said frame 1. The said lug 7 and cross bar 8 are provided with corresponding centrally placed holes adapted to receive a suitable pin such as for instance a split pin 9 illustrated in Fig. 3. Instead of a pin such as 10 illustrated, or bolt or the like we may attach said top part to its frame by bayonet connections which will normally hold said top part in position, so that it cannot fall off its frame in any position on the carriage 15 on which the chain is mounted; such bayonet connections may comprise bayonet recesses on the inner surface of each side of the frame, adapted to receive engaging members 20 projecting laterally from the under surface of the top portion.

One method of utilizing our invention is illustrated in Fig. 7, which shows a complete chain grate. The flap fire-bars are mounted on the transverse bars 2 of the 25 chain 10, which is moved in the direction of the arrow by the sprocket 11. The chain 10 is supported by upper guide rollers 12 and lower guide rollers 13, journaled in the movable carriage 14. Upon the return 30 movement of the links or fire-bars, toward the front of the carriage, they turn like flap valves at points intermediate the rollers 13, thus dumping any partially consumed fuel or ashes which may have 35 dropped from the top portion to the lower portion of the chain.

What we claim and desire to secure by Letters Patent of the United States, is:—

1. A flap firebar for chain grates comprising a frame having means for pivotally connecting one end only to a grate chain, a removable top, said frame having an undercut portion at the hinged end thereof, there being a projection on the removable top adapted to be seated in the undercut portion of the frame, and means for securing the other end of the top to the frame, substantially as described.

2. A chain grate stoker comprising a plurality of chains, grate bar supporting members connected to said chains, a series of bars pivotally connected each at one end only to said supporting members, each of said grate bars comprising a frame and a removable top, the frame having an undercut portion and the top having at one end a projection adapted to be seated in the undercut portion, and means for securing the other end of the top to the frame, the arrangement being such that the top is adapted to fall downwardly from the frame when said securing means is inactive and the grate bar is vertically suspended from its supporting member, substantially as described.

In testimony whereof we have hereunto signed our names in the presence of two subscribing witnesses.

CYRIL GEORGE MANCHA BENNETT.
SYDNEY HERBERT SMITH.
